HOLDER FOR KITCHEN COOKING UTENSILS OR THE LIKE

Irma L. Van Antwerp, 3295 Shady Side Drive,
Grand Rapids, Mich.

Filed Apr. 20, 1964, Ser. No. 79,614

Term of patent 14 years

(Cl. D44—29)

FIG. 1 is a top perspective view of a holder for kitchen cooking utensils or the like showing my new design; and FIG. 2 is a bottom perspective view.

I claim:
The ornamental design for a holder for kitchen cooking utensils or the like, substantially as shown.
